DISPLAY RACK

Nickolas J. Halip, 485 Shelbourne, Grosse Pointe Farms, Mich. 48236

Filed Sept. 14, 1967, Ser. No. 8,592

Term of patent 14 years

(Cl. D80—10)

The characteristic features of my design reside in the portions shown by means of full lines.

I claim:

The ornamental design for a display rack, substantially as shown and described.
